WINDOW SASH-BALANCING MEANS

Lance E. Appleby, Wichita, Kans.

Application September 3, 1932, Serial No. 631,616
Renewed October 12, 1936

2 Claims. (Cl. 16—198)

My invention relates to window sash-balancing means.

The object of my invention is to provide a spring actuated pendant supporting means for the sash, and means to adjust the tension of the 5 springs for sashes varying in weight.

A further object of my invention is to provide a simple and efficient means to wind or unwind the springs and accessibility thereto without the removal of any portion of the window frame.

10. A still further object of my invention is to arrange a head jamb for the window frame, as supporting means for the sash balance mechanism, the jamb removable, carrying the mechanism therewith after the frame has been installed and 15 cased.

20. A still further object of my invention is to provide a pair of springs each of which consists of two coils varying in diameter so that one will engage within the coils of the other and secured together at one end to increase winding and rebound capacity.

25. A still further object of my invention is to eliminate the conventional weights and pulleys commonly employed; a window frame may be installed practically air-tight, and furthermore the expense reduced by the adoption of narrow casings as the studdings adjacent the jambs are placed in close proximity thereto and to which the outer edge of the casings may be secured, 30 the same not being possible with the required space for weights between the jamb and the studding as commonly employed.

35. These and other objects will hereinafter be more fully explained, reference being had to the accompanying drawings forming a part of this specification and in which like characters will apply to like parts in the different views.

Referring to the drawings:

40. Fig. 1 is an inside elevation of a cased window.
Fig. 2 is an outside elevation of the window.
Fig. 3 is an enlarged cross section of the mullion of a double window.

45. Fig. 4 is a cross section through a window sill and portion of the wall.

Fig. 5 is a cross section through the head jamb, exterior and interior trim and lintel.

Fig. 6 is a cross section through the side jamb, sash, trim, and portion of the wall.

50. Fig. 7 is a sectional view of an extension jamb.
Fig. 8 is an elevation of an upper corner of the frame, fragmentarily shown.

55. Fig. 9 is a side view of a fragmentary portion of the apertured bar carried by the side rail of the sash.

Fig. 10 is a plan view of the sash balancing means with parts removed for convenience of illustration.

Fig. 11 is an inverted plan view of Fig. 10.

Fig. 12 is an end view of Fig. 10, outside plate removed, and one sheave sectionally shown.

Fig. 13 is an enlarged elevation of the spring winding mechanism, the shaft fragmentarily shown.

Fig. 14 is an inverted view of the winding gear.

Fig. 15 is a plan view of one end of the winding gear housing showing transversely positioned slots.

Fig. 16 is an elevation of an upper corner of the lower sash and tape fragmentarily shown.

Fig. 17 is an exploded view of the sheave and component parts.

Figs. 18 and 19 are inside end views of the drum portions of the sheave.

Fig. 20 is a plan view of the lock with a portion of the housing removed, also jamb and sash associated therewith, the latter being in cross section.

Fig. 21 is a sectional view taken on line 21—21 in Fig. 20, looking in the direction of the arrows.

My invention herein disclosed consists chiefly in a balancing means for window sash and also special features in connection with the window frame consisting of side jambs 4 and sill 2, and a head jamb 3, the latter removably arranged, and on which the balancing means is carried and removable therewith. I have also arranged a housing 4 for the balance mechanism, the said housing is rigidly attached to the side jambs by nailing the same to their respective ends of the housing.

Furthermore, I have formed on the inside of the upper end portion of each jamb a shoulder 5 on which the ends of the housing will seat, as shown in Fig. 8. The purpose of the housing is to permanently connect the ends of the jamb and to protect the balance mechanism from mortar or other debris contacting therewith.

Positioned in close proximity to each end of the said head jamb is a bearing consisting of an inside vertically disposed member 6 having a base A integral therewith, and at right angles thereto as supporting means and attached to the head jamb by a screw 7 as shown by dotted lines in Fig. 12, and an outside member 8, in parallelism with member 6, each member being apertured in registry as shown at B in Fig. 5, and in which the outer ends of rods 9 will rotatably engage for the purpose later described.

The said outside plates have a tongue 10 bent

at right angles to engage with the inside member, as spacing means for the upper portion of said members. It will be understood that the apertures of the inside bearing members are greater than those in the outside to receive the hub 11 of one of the inside portions of the sheaves. The sheaves are composed of two parts, an inside and an outside portion. Each portion has its respective flange 12 and 12' forming a drum intermediately positioned consisting of two parts, male and female, telescopically engaging. The male portion 13 has a flat side as at C and the female portion 14 has a slot D through the side thereof and through which the end of a tape 14 will extend, resting on the flat portion when the said members are brought to engagement forming the sheave as shown in Fig. 10 and revolved in opposite direction to bind the tape when the side of the slot and the terminating side of the flat portion are moved in close proximity binding the tape, and retained in such portion by a notch 15 engaging with a lug 16, by which means further rotation is obviated. The said tape being wound on the portion 14 is the pendant supporting means for its respective side of the sash, and being connected thereto through the medium of a screw 17 threadedly engaging in the sash and passing through the aperture in the lower end of a T member 18 as shown in Figs. 12 and 16. The said tape is free to slidably engage in a slot 19 in alignment therewith and passing through the ends of the head jamb respectively.

Secured to the hub 11 of the inside member of the sheave is a sleeve 20 snugly fitting thereon and having a flange 21 spaced from the inner end thereof, to which the end of coil spring 22 is secured by a short bend as at E inserted through an aperture passing through the flange as turning means for the sheave when wound to the proper tension for the weight of the sash pendants carried by the tapes, there being a similar sheave and tape for each side of the sash. In coaction with the said spring 22 is another spring 23 within the coil of the first said spring, and through which a rod 9 extends; the said rod also extending through the members of the sheave which are axially bored to receive the same and free to revolve therein, as the springs are tensioned, the method of which is later described.

The end of the last said spring adjacent the sleeve element to which the first said spring is attached, is secured to the rod by the end portion extending through an aperture diametrically as shown at F in Fig. 10. The other end of each of the springs is secured to an annular flange 25 that is rotatable on the rod, each spring being attached by a short bend at the end portion extending through apertures respectively in the said flange as shown at G and H. The spring elements thus arranged will avoid excess buckling when highly tensioned by lowering the sash, the said springs coacting with each other, the inside spring unwinding against the wind of the outside spring, each being tensioned in opposite directions to equalize the tension required at the extreme upper position of the sash. It being understood that the said rod remains stationary after the springs are properly adjusted and to adjust the said springs, there is positioned on the longitudinal center of the head jamb a bearing consisting of a channel like structure, the parallel sides of which upwardly extend as shown at 75 26 and 26' in Figs. 10, 13 and 15, each side hav-

ing its respective half of the apertures functioning as bearings in which hubs 27 of gears 28 are trunnioned; the said hubs are bored axially to engage their respective rod rigidly when passed therethrough as rotating means therefore through the medium of gear 29 that is trunnioned in the base of the channel as shown in Fig. 13, the bearing for said gear 29 arranged by a downward extension 30, through which a stem 31, secured to the gear, extends as turning means 10 therefor.

The said stem has a slot 32 in the lower end thereof to receive a screw driver when turning the same. In the lower end of the extension is a disk 33 movable with the gear 29 when forced upward by which means the said gear is retracted to its normal position through the medium of a spring 34 interposed within the extension bearing upon the disk and the base portion of the channel.

Arranged and extending downward from the underside of gear 29 is a pair of lugs 35 oppositely and radially extending as shown in Fig. 14, the said lugs adapted to seat in radially positioned slots 36 transversely crossing each other as shown in Fig. 15 by which means when the said gear 29 retracts to its normal position it is locked against rotation but is free to turn when forced upward by a screw driver sufficient to disengage the said lugs from their respective slots 36, the teeth of the gears being in mesh at all times.

It is now clearly shown how the said springs are wound to the required tension balancing the sash. The said bearing previously described has a cap element 37 to snugly engage over the channeled bearing and has in its sides the other half of the bearing in registry with those previously described, and means to secure the cap to the bearing through the medium of a screw 38 in each end thereof to threadedly engage in a threaded aperture in an upturned lip 39 as shown in one end of the bearing illustrated in Fig. 10.

In actual practice the spring balancing mechanism is wound to maintain the weight of the upper sash, making it possible to stop the same at a desired open or closed position, but the lower sash spring balancing means is preferably tensioned sufficiently to raise the same.

Positioned on the adjacent side of the sash to the latch is a channel 53, embedded in the side rail thereof and secured thereto against longitudinal movement and having spaced therealong a plurality of rectangular apertures 54 spaced apart and in which the said latch will engage selectively. It will be understood that the apertured channel may extend the full length of the side rail of the sash, by which means the lower sash may be raised partially and locked against further upward movement and to permit further movement of the sash the rod 49 is pushed inward releasing the sash. The sash may be checked at a desired position by releasing tension on the push rod.

It is now clearly shown how a room may be ventilated by partially opening the lower sash and locking the same against further open movement as the said push rod is positioned in close proximity to the check rail of the sash when normally closed.

It is now shown that by the elimination of weight pockets formerly employed or provided for in the installation of window sash the studing of a frame building may be placed in close proximity to the back of the window jamb af-

fording means to which a narrow casing may be attached by nailing the same thereto which is economy, and the space between the studding and the jamb may be calked, and as a whole the 5 frame may be installed and cased practically air tight. Provision is also made for the application of stucco as shown at K in Fig. 6 by placing a groove as at L on the inner and outer corner of a brick mould 55 and provision is further 10 made when the structure is veneered with brick in which case the brick mould must close the space between the brick and the sheathing of the structure, and to move the said brick mould outward carrying the jambs therewith, I have pro- 15 vided an extension jamb member 56 having a tongue 57 thereon to engage in grooves 58 as shown in Figs. 3 to 6 inclusive, by which means the jambs are brought flush with the inside plas- 20 tered wall on which the casing will engage.

Such other modifications may be employed as lie within the scope of the appended claims, and having fully described my invention what I claim as new and desire to secure by Letters Patent is:

1. In a window sash-balancing means of the class described, a rod, a sheave secured near each end of the rod, a bearing for each sheave, the rod extending therethrough to engage with one side of the bearing, the sheave having a hub on the other side to engage with its respective side of 25 the bearings by which means the said rod is trunnioned, and the sheave free to rotate thereon, each of the sheaves having a tape wound thereon, the free end of each tape being attached to its respective side of a sash, a spring wound 30 on the shaft adjacent each sheave, the end of the spring adjacent the sheave being secured to the shaft, another spring wound about the first said spring and having one end thereof secured to the hub of the sheave, an annular flange ro- 35 tatable and slidble on the rod, the flange as connecting means for the other end of each spring, a bearing intermediately positioned to the first said bearings, all of said bearings being secured to the upper side of the head jamb of the

window frame, a toothed gear having a hub to engage in said bearing, the hub axially bored to receive the rod as turning means therefor, the points of the gear teeth being in a plane trans- 5 verse to the axis of the hub and a gear trun- nioned in mesh with the first said gear and adapted to move axially while in mesh there- with and means to turn and lock the last said gear against rotation when the said springs are tensioned sufficiently. 10

2. A window sash-balancing means of the class described comprising a rod having a sheave rotatable on each end thereof and a bearing for each sheave and its adjacent end of the rod, each sheave having a flanged hub on the inner side thereof, a pair of springs one of which is positioned within the other and through which its respective end portions of the rod extends, the end of the inside spring being secured to the rod adjacent the flanged hub and the corresponding 20 end of the outside spring secured to the flange of the hub, an apertured flange loosely engaging on the rod adjacent the other end of the springs and to which the said flange is secured by which means the said sheaves are rotatably tensioned, 25 a tape wound on each sheave, the free ends thereof secured to their respective sides of a sash as carrying means therefor, a bearing medially positioned with respect to the rod longitudinally and a gear secured to the rod and trunnioned 30 in the bearing, a second gear carried by the said bearing and in mesh with the first said gear, the last said gear adapted to move toward and from the axis of the first said gear as turning means therefor when the last said gear is moved inward 35 and turned, means on the last said gear to engage with the bearing to avoid rotation when returned to its normal position, by which means the said springs are wound to a preferred ten- sion and secured as balancing means for the 40 sash, all of said bearings carried on the head jamb of a window frame.

LANCE E. APPLEBY.
